UNITED STATES PATENT OFFICE.

ROY T. AXE, OF SYRACUSE, NEW YORK, ASSIGNOR TO THE O. M. EDWARDS COMPANY INC., OF SYRACUSE, NEW YORK, A CORPORATION OF NEW YORK.

MULTIPLE-WINDOW CONSTRUCTION.

Application filed March 11, 1926. Serial No. 94,041.

This invention relates to window sash construction and particularly a construction in which there are a plurality of sashes one arranged in front of the other, and has for 5 its object a particularly simple and efficient construction and arrangement of the window guides whereby the guides of each sash abuts against the guides of the next sash and hence the removal of the sashes when 10 necessary is readily effected by the removal of the sashes and the guides in succession.

The invention consists in the novel features and in the combinations and constructions hereinafter set forth and claimed.

15 In describing this invention reference is had to the accompanying drawings in which like characters represent corresponding parts in all the views.

Figure 1 is a large fragmentary transverse 20 vertical sectional view through the window frame and sashes.

Figure 2 is a sectional view on line 2—2, Figure 1.

This sash construction is particularly 25 adapted for marine windows or windows used in ships, where there are a plurality of sashes, the outer sash embodying a glass pane, the middle sash, a screen and the inner sash a blind; and it comprises a window 30 frame, a plurality of sashes of equal width arranged one in front of the other in the frame, the sashes having a raising and lowering movement and guides for the sashes, these guides projecting from the frame into 35 the window opening and slidably interlocking with the sashes, and each guide abutting against the next guide, whereby upon the removal of the outermost guide with its sash, the next guide and its sash are accessible 40 for removal and then the next innermost is accessible for removal; and also whereby the sashes can be readily assembled in a window opening by first placing in position the innermost sash and its guide, then the next sash 45 and its guide abutting the latter guide against the first guide and last by the third sash and its guide.

1 designates the frame, which may be of 50 any suitable form, size and construction. Three sashes are here shown and 2, 3 and 4 designates respectively the outer, middle and inner sash. The outer sash carries the glass 55 pane 5, the middle sash a screen 6 and the inner sash a blind 7. The sashes are here shown as comprising a hollow sheet metal

sash member, that is hollow sheet metal stiles and rails, and the stiles 8 are in the form of a channel open at their edges for receiving the window guides.

Each window guide has a portion 9 projecting into the channel of the stile 8 and a base plate 10 which abuts against the guide for the next sash. These guides are formed up of sheet metal strips.

The base plate portions 10 is secured to 65 the frame by screws 11.

The middle guide abuts against the innermost guide and the outer guide abuts against the middle guide at 12 and 13. The base portion 14 of the outermost guide is flush 70 at its edge with the outer side of the frame. The outermost guide is also held in position by one or more screws as 15 extending through the guide portion 9 thereof into the frame, this screw 15 being only accessible 75 when the sash is elevated so that when the sash is lowered and locked the window cannot be removed by taking out the screws 14 and thus removing the outer sash and its guide making accessible the screws 11 80 of the middle guide so that the middle sash can be removed and thus ingress obtained to the compartment provided with the window.

Each sash is provided with a suitable lock 85 16 which coacts with the corresponding window guide or projecting portion 9 thereof to hold the sash lock in closed position or elevated position.

This lock forms no part of this invention, also the sash construction forms no part of this invention but forms the subject matter of other pending applications.

What I claim is:—

1. A window sash construction comprising 95 a frame, a plurality of sashes carried by the frame, one in front of the other, removable guides for the sashes respectively, the guides for the outer sash abutting against the guides for the sash in the rear thereof 100 and means for securing the guides to the frame and means for securing the guide for each sash located in front of the companion sash whereby the guide is detachable while the sash is engaged therewith in order that 105 the sash and guide may be removable as a unit.

2. A window sash construction comprising 110 a frame, a plurality of sashes of equal width carried by the frame, one in front of

- the other, removable guides for the sashes respectively, the guides for the outer sash abutting against the guides for the sash in the rear thereof, each guide comprising a 5 guide portion for the companion sash and a base strip forming a spacer between it and the next guide and means extending through the base strip for securing the guides to the frame.
- 10 3. A window sash construction comprising a frame, a plurality of sashes of equal width carried by the frame, one in front of the other, guides for the sashes respectively, the guides for the outer sash abutting against

the guides in the rear thereof, each sash 15 being formed with a channel in each side edge thereof, and each guide having a guide portion projecting into the channel of the companion sash and a base portion forming a spacer abutting against the next guide, 20 and means for securing the guides to the frame, said means extending through the base portion of the guide.

In testimony whereof, I have hereunto signed my name, at Syracuse, in the county 25 of Onondaga, and in the State of New York, this 5th day of January, 1926.

ROY T. AXE.
